(57) **CLAIM**

The ornamental design for a bait boat, as shown and described.

DESCRIPTION

1. Bait boat

1.1 : Front

1.2 : Back

1.3 : Top

1.4 : Bottom

1.5 : Right

1.6 : Left

1.7 : Perspective

1.8 : Perspective

1.9 : Perspective

1.10 : Perspective

Design has rear hopper engineered to ensure that bait remains dry and secure; Its contours not only enhance aesthetics but also optimize functionality by stable drive and silent operation; The inclusion of a modular sonar system empowers anglers easy upgrade sonar to newer modules, adapting to diverse fishing conditions; Furthermore, the hassle-free removable motor protection mechanism simplifies maintenance, guaranteeing seamless operation.
